“Commercial Electric” 7-inch diameter Easylight LED lamp Model 1000 016 474, marketed by Home Depot in USA (2015), four (4) views (2 pages, color).

* cited by examiner

Primary Examiner — Clare E Heflin(74) *Attorney, Agent, or Firm* — Andrew Martin(57) **CLAIM**

The ornamental design for a lamp, as shown and described.

DESCRIPTION

FIG. 1 is a perspective view of the new design for a lamp as seen from the rear, side;

FIG. 2 is a side elevational view thereof, views from other sides being the same, the design being rotationally symmetric;

FIG. 3 is a bottom plan view thereof; and,

FIG. 4 is a top plan view thereof.

The broken line disclosure is for environmental purposes only and does not form a part of the claimed design.
